HAROLD E. HOUSEMAN, OF EDGE MOOR, DELAWARE, ASSIGNOR TO STANDARD-TRUMP BRO. MACHINE COMPANY, OF WILMINGTON, DELAWARE, A CORPORATION OF DELAWARE

PATTERN MECHANISM FOR CIRCULAR KNITTING MACHINES

Original application filed May 20, 1926, Serial No. 110,311. Divided and this application filed June 23, 1928. Serial No. 287,408.

This application is a division of an application filed by me May 20, 1926, Serial No. 110,311, Patent No. 1,769,580. In said application is disclosed a complete machine for knitting hosiery of multicolored patterns, particularly striped hosiery. The said machine comprises certain novel yarn carrier operating devices, and also certain pattern and selecting mechanism which control the operation of the yarn carrier operating devices. The said devices, which are operable from the driving means, are rendered differentially operative by selecting means, which are in turn controlled by a pattern chain, which is preferably operated by reciprocatory means that also operates the yarn carrier operating devices. The said devices, in their movement in one direction, are engaged and positioned by the selector, and in their reverse movement operate the yarn carriers.

The needle cylinder is adapted to rotate and oscillate as usual. Means are operated from the machine drive to cause the pattern and selecting mechanism to operate upon said yarn carrier operating devices during rotation, to render said mechanism inoperative to operate upon said devices during oscillation, to stop the pattern chain during the knitting of the heel, and to render the selecting means inoperative by the pattern chain at the beginning of toe knitting and to subsequently stop the pattern chain at a definite point. The pattern chain is so carried on the machine that it can be readily removed and another pattern chain substituted; the new pattern chain, if not adjusted by hand, being advanced by its drive and then subsequently stopped at the said definite point.

The means for differentially operating the yarn carrier operating devices, including particularly the pattern and selecting mechanism, is obviously not limited in its utility to the operation or control of yarn carriers, but is applicable to the operation or control of devices that control or operate mechanism that may cooperate in the knitting operation in various other ways. The subject-matter of this application comprises the pattern, selecting and driving mechanism for such devices; the various other features of novelty

disclosed in the parent application being therein claimed. In order, however, to disclose a useful application of the invention herein claimed, the machine of the parent application, showing the adaptation of the invention to the operation and control of yarn carriers, is herein described, and shown in the drawings, in which—

Fig. 1 is a plan view of the parts of a circular knitting machine embodying the invention.

Fig. 2 is a side elevation of the same looking toward one side of the machine.

Fig. 3 is a side elevation, partly in section, of the yarn changing mechanism, looking toward the other side of the machine.

Figs. 4 and 5 are similar views of a portion of the mechanism shown in Fig. 3, with the parts in different positions.

Fig. 6 is a rear elevation of the devices for actuating the yarn fingers and yarn finger retainers, the selector, the pattern chain, and associated mechanism.

Fig. 7 is an enlarged cross-section through the cam disc of the machine on line 6, Fig. 2.

Fig. 8 is a perspective view of the cams for primarily controlling the operation of the pattern chain, looking in the direction of the arrow, Fig. 7.

Figs. 9 and 10 are detail views of the mechanism for immediately controlling the operation of the pattern chain.

a is the needle cylinder of a circular knitting machine. This cylinder may be driven from the main shaft so as to have imparted to it a movement of continuous rotation or a movement of oscillation, as is well known in the art. Any known mechanism for so operating the cylinder and for shifting, and for controlling the shift, from rotation to oscillation and vice versa may be employed, as, for example, the mechanism shown in the patent issued to me December 24, 1918, No. 1,288,594.

In the present case, I have shown a main driving shaft *b* which, through a bevel pinion *c*, drives a bevel gear *d*. The latter carries a spur gear which drives a pinion *e* on the shaft of a gear wheel *f*. From the latter the

needle cylinder is driven by means not shown. See Figs. 3 and 6.

The machine is equipped with any desired number of yarn fingers 10. Five are shown, 5 three being used for striping and operated in accordance with my invention. Each yarn finger is pivotally supported on a suitable part of the machine frame and is normally held out of operative position, as shown in 10 full lines in Fig. 3, by a spring 13. In the specific construction shown, each finger 10 gears with a pivoted lever 11, whose free end extends between the forks of a rock lever 12, which is normally held, by the spring 13, in 15 position to hold finger 10 out of action. Each lever 12 is positively operable, by a corresponding lever 14 pivoted on the frame, to swing yarn finger 10 down into action.

Each yarn finger 10 is provided with two 20 notches, one or the other of which (dependent on whether the finger is moved up out of action or down into action) is engaged by a retainer lever 20 suitably pivoted on the frame and maintained in holding position 25 by a spring 21. Pivoted on the same axis as lever 20 is a frame 22 having a hooked end 23 (extending under the free ends of levers 20) and a depending arm 24, the end of which is shown in Figs. 3, 4 and 5 and the whole 30 of which is shown in Fig. 2. The main function of the retaining levers 20 is to hold in active position the corresponding yarn finger 10 after it is depressed by the lever 14 acting through levers 12 and 11.

Pivottally mounted on the machine frame 35 is a laterally extending bell crank lever 31 (see Figs. 1 and 6), one arm of which has a pin which rides in a cam groove 30 in gear wheel *f*, which imparts to lever 31 a constant reciprocatory movement. The other arm of 40 the reciprocating lever 31 carries an upright arm 32 having a laterally extending end on which are pivoted a series of devices 33 each shaped like a bell crank (see Figs. 3, 4 and 5). These devices 33 operate the respective 45 levers 14 but are normally held, by springs 34, in such position, as shown in Fig. 3, that, in their forward swinging movement, they do not engage levers 14. If, however, any 50 one of the devices 33, in its movement of recession, is tilted to the position shown in Fig. 4, then, in its next forward movement, it actuates the corresponding lever 14, as shown in Fig. 5, thereby moving down into 55 action the corresponding yarn finger 10. During such forward movement of device 33, its forward bevelled end slides over and above the rear bevelled end of lever 14, the upward 60 tilting movement of device 33 being limited by a stop 39.

The arm 32 of reciprocating lever 31 also carries a pivoted bell crank lever 35, which at one end carries a cross-bar 36 and at its other end carries an adjustable screw 37.

65 Lever 35 is normally held in inoperative po-

sition by a spring 38. When, however, any of the devices 33 is tilted into operative position and is carried forward by arm 32 to actuate the mechanism for moving into action a corresponding yarn finger 10, such device swings lever 35 into such position that, in the continued forward movement of arm 32, lever 35 strikes the end of arm 24, tilting frame 22 and lifting all the retaining levers 20, thus allowing any yarn carrier that has been previously down in operative position to be swung up into inoperative position by its corresponding spring 13.

On the next receding movement of arm 32, lever 35 first recedes from arm 24, allowing springs 21 to move the retaining levers 20 again into engagement with the respective yarn fingers 10, thereby holding in operative position the yarn carrier that has been moved into action.

The described parts are so positioned that the tilted device 33 effects a movement into operative position of the corresponding yarn finger 10 appreciably before the lever 35 effects the lifting of the retaining levers 20, so that, for an appreciable time (say one two hundredths of a second and while the needle cylinder is revolving throughout an arc subtending four needles), two yarn fingers are simultaneously in action. This effects an overlap of yarn in the fabric being knit. The movement of one yarn finger into operation just before the withdrawal of another yarn finger is common in the art; but in addition to this mode of operation, the above described construction affords a ready means of predetermining exactly the length of the overlap, such means being the screw 37, by whose adjustment the exact movement of withdrawal of the retaining levers 20 after the movement into operation of a yarn finger can be accurately controlled.

The tilting of the devices 33 is effected by means of a selector 40 shown in Figs. 2, 3, 4, 5 and 6. Selector 40 is movable into a number of different positions, as shown in Fig. 6. Except when a yarn change is to be made, the selector is in an inoperative position (one of the broken line positions). During rotary knitting, selector 40 normally occupies the broken line position at the right, Fig. 6. During the oscillation of the needle cylinder while knitting a plain heel or toe, it occupies one of the broken line positions at the left. When, however, during rotary knitting, it is desired to effect a yarn change, the selector is shifted to a position behind one of the tiltable devices 33. In Fig. 6 it is shown as behind the middle one of the devices 33. In the receding movement of arm 32, after selector 40 has been so positioned, the middle one of the devices 33 is tilted, from the position shown in Fig. 3, to that shown in Fig. 4, so as to position it to subsequently effect the movement into operative

70

position of the corresponding yarn carrier 10 and the lifting of all the retaining levers 20, as above described. Selector 40 is under tension of a spring 41 to allow device 33 to slightly tilt the selector backward in the completion of the receding movement of arm 32 to allow the front bevel of device 33 to override and, in the beginning of its succeeding advance movement, just overlap the rear bevel of the corresponding lever 14, as shown in Fig. 4, and thus set the device 33 in operative position. During this advance movement of arm 32, the selector is shifted to the right, Fig. 6, out of alignment with the devices 33, so that on the next receding movement of arm 32, the just actuated device 33 will return to the inoperative position shown in Fig. 3.

A distinctively advantageous feature of my new machine is that the same element (lever 31) that reciprocates the devices 33 for controlling yarn changes also effects (indirectly) the shifting of the selector 40 into position to effect any desired yarn change. The selector is more nearly directly actuated by a pattern chain 50 (see particularly Fig. 6) carrying lugs 51 of three different heights. These three lugs are adapted to underride a lever 60 and lift it so as to tilt into three different positions a bell crank lever 42 carrying the selector 40 and shift it from the broken line position shown at the right in Fig. 6 to a position back of the first, second or third of the devices 33, dependent on whether the operating pattern chain lug is a low lug, a medium lug, or a high lug. The pattern chain is operated by a sprocket wheel 52 carrying a ratchet wheel 53, which is engaged by a pawl 54 (see Figs. 6, 9 and 10) on the reciprocating lever 31. Thereby, as above stated, lever 31 carries the devices 33 that effect the selective operation of the several yarn fingers 10 and also imparts a step-by-step movement to pattern mechanism controlling the selector 40 that selectively actuates devices 33.

In the shift from rotation to oscillation, preparatory to knitting the heel, it is necessary to arrest the movement of the pattern chain so that, on the return to rotation and the resumption of circular web knitting, the pattern in the front of the web will be continued where it left off at the conclusion of the previous period of rotation. The movement of the pattern chain is arrested, in a very simple manner, by means of a pawl guard 61, which is lifted from a position below that shown in Fig. 9 (where it does not affect the pawl 54) to the position shown in Fig. 10, in which position it lifts the pawl 54 out of action. Pawl guard 61 is lifted by the lifting of lever 60 above the position to which it is lifted by the highest lug on the pattern chain. When lever 60 is so lifted, it swings the selector-carrying lever 42 into the extreme left-hand broken line position shown

in Fig. 6, which is one of the inoperative positions of the selector.

This high lifting of lever 60 is effected by means of a cam 71 carried by a pattern disc 70. See Figs. 7 and 8. This pattern disc 70 may be intermittently operated from the machine drive by any suitable means, as, for example, that shown in the patent issued to me June 4, 1921, No. 1,364,112. The term "pattern disc" is intended to include any device 75 carrying the cam 71 (and the cams 72 and 73 hereinafter described) and which is operable in proper sequence relative to the means for changing from rotation to oscillation, and vice versa. Cam 71, it will be understood, 80 operates lever 60 at the beginning of the shift from rotation to oscillation preparatory to knitting the heel and releases lever 60 at the conclusion of such oscillating period. 85

In timed relation to the shift from rotation to oscillation preparatory to knitting the toe, it is necessary to again arrest the movement of the pattern chain; and when it is desired to begin the knitting of the pattern 90 after the return shift from oscillation to rotation and after knitting of a new stocking is started, it is necessary to restart the pattern chain. It is obviously desirable, however, to start the pattern at the beginning and 95 therefore the pattern chain should not be arrested until it is brought to the definite position that it must occupy in order to start the pattern at the beginning. To effect this operation of stopping and restarting in timed 100 relation to the said shifts, it is necessary to restart the pattern chain at a definite course of knitting; but the time of arrest of the pattern chain preceding such restarting will vary with the position of the pattern chain 105 after the yarn fingers used for striping are moved out of action preparatory to knitting the toe; and such arrest may occur during rotation immediately preparatory to the shift to oscillation or during such oscillation, 110 while the restart of the pattern chain will occur after rotation is resumed. This will be clear from the following explanation.

Preparatory to knitting the toe, it is customary to knit several plain round courses. In the present machine, therefore, it is arranged that all the yarn carriers used for striping shall be moved out of action preparatory to knitting these plain round courses; and it is arranged that the pattern chain shall thereafter continue to advance until it is brought to the definite position that it must occupy in order to start the pattern at the beginning and shall not be arrested until it is brought to that position. This movement of arrest may occur while the machine is knitting plain round courses or after the subsequent shift from rotation to oscillation and while it is knitting the toe—dependent 125 on the length of chain that must be ad- 130

vanced until the chain is brought to such definite position. After the toe is completed and the machine is reshifted from oscillation to rotation, it is customary to knit several looper rounds and, after transferring, to knit several rounds of plain knitting and then restart the pattern. In the present machine, therefore, it is arranged, after the desired number of rounds of plain knitting, to restart the chain and thereby restart the knitting of the patterned part of the stocking.

To effect the above described operation, I provide devices on the pattern chain and lever 60 which cooperate to stop the chain at the proper point, and to thereafter restart the chain, as will now be described.

Preparatory to knitting the plain round courses preceding the toe, a cam 72 on pattern disc 70 engages lever 60 and swings it into the position shown in Fig. 9, whereat lever 60 is shown lifted high enough to allow the lugs on the pattern chain to travel under the lever 60 but not so high as to lift guard 61 high enough to prevent the continued ratcheting of the pattern wheel by the pawl 54. (In this position of lever 60, lever 42 is swung into the broken line position next to the extreme broken line position at the left in Fig. 6.) In this position of lever 60, an arrester cam 62 on lever 60 is brought into such position that a shifter or set-up pin 55 (Fig. 6) on the pattern chain will (at the point at which it is desired to stop the pattern chain) underride arm 62 and lift lever 60 into the position shown in Fig. 10, at which position, as hereinbefore explained, and as Fig. 10 clearly shows, guard 61 will lift pawl 54 out of operative position. It will remain in this position even after cam 72 rides beyond lever 60. After the knitting of the toe is completed and after the shift from oscillation to rotation and after the previously described round courses are knit, an extra high cam 73 rides under lever 60 and lifts it to a position higher than any hereinbefore described and sufficiently high to cause a second pawl 63 (carried by lever 60) to engage the ratchet 53 and advance the pattern chain one step, the pin 55 then riding beyond arm 62. Immediately thereafter cam 73 rides beyond lever 60, permitting lever 60 to return to its normal position, in which position pawl guard 61 drops down into operative position, allowing the pawl 54 to resume the step-by-step operation of the pattern chain.

A clamp-and-cutter actuating lever 80 (see Figs. 1 and 2) is pivoted on the machine frame. Lever 80 is operated, synchronously with the yarn changing mechanism, by means of an arm 25 (on frame 22) underriding an adjusting screw 81 carried by lever 80. The clamp and cutter mechanism may be the same as that set forth in an application filed by me June 19, 1925, Serial No. 38,162.

It will be noted that the described pattern

mechanism comprises the pattern chain 50 and the cams on the disc 70; and that the cam-carrying disc acts as a primary pattern mechanism and that the chain acts as a secondary pattern mechanism. Obviously these two pattern mechanisms need not be respectively a "disc" and a "chain," as equivalent pattern devices are known in the art.

One notable advantage of a machine embodying my invention is that a change of pattern may be made very quickly. In the ordinary knitting machine, a change of pattern involves the stopping of the machine for several hours while the pattern mechanism is being adjusted to knit a new pattern. In my machine it is only necessary to slip off one chain and substitute another chain the lugs of which were arranged to dictate the knitting of a new pattern while the machine was in operation. This change occupies but a few seconds and, indeed, may be effected while the machine is knitting the toe. Moreover, the chain need not be accurately positioned, because it will automatically properly position itself by the engagement of the described cooperating devices 55 and 62 on the pattern chain and lever 60 respectively.

Having now fully described my invention, what I claim and desire to protect by Letters Patent is:

1. In a circular knitting machine, the combination with mechanism adapted to cooperate in the knitting operation and to be selectively operated, of a set of independently operable devices adapted to selectively operate said mechanism, operating means carrying said devices, selecting means which are adapted to be engaged by and position said devices as they are moved by their operating means, and pattern mechanism adapted to move the selecting means into position to selectively position said devices so that, in their subsequent operation by their operating means, they will selectively operate said mechanism.

2. In a circular knitting machine, the combination with a set of differentially positionable devices, of pattern mechanism, a contrivance adapted to operate said pattern mechanism and carry said devices, selecting means operable from the pattern mechanism and adapted to be moved into position to differentially position said devices as they are moved by said contrivance, and means to operate said contrivance.

3. In a circular knitting machine, the combination with a set of independently operable devices, of means adapted to operate said devices, said means comprising a contrivance carrying said devices and a selector adapted to render any of said devices operative, and pattern mechanism actuatable by said contrivance and adapted to actuate said selector.

4. In a circular knitting machine, the com-

bination with independently operable devices, of a selector adapted to be shifted into positions to selectively operate said devices, pattern mechanism adapted to shift the selector into different operative positions, and means to continuously reciprocate said devices, said continuous reciprocation effecting the operation by the selector of the device that is in operative relation therewith.

- 10 5. In a circular knitting machine, the combination with selectively operable devices, of a selector adapted to be shifted into different positions to selectively operate said devices, pattern mechanism, means operated by the pattern mechanism to shift the selector into different operative positions, and continuously reciprocating mechanism adapted to operate said devices and impart a step-by-step movement to the pattern mechanism.
- 15 6. In a circular knitting machine, the combination with devices which are both continuously reciprocable and independently shiftable into operative and inoperative positions, means to reciprocate said devices, a selector adapted to be moved into position to selectively shift said devices, in their movement in one direction, into operative position to be actuable in their movement in the other direction, and pattern mechanism adapted to shift the selector into different operative positions.

20 7. In a circular knitting machine, the combination with devices independently movable into operative position, of a selector adapted to be shifted into positions to selectively shift said devices into operative positions, pattern mechanism, means operated by the pattern mechanism to shift the selector into different operative positions, and continuously reciprocating mechanism adapted, in its movement in one direction, to actuate the pattern mechanism to shift the selector, and in its movement in the other direction to cause the selector to selectively move said devices into operative positions, and in its movement again in the first direction to cause said devices to operate.

25 8. In a circular knitting machine, the combination with a rotatable and oscillatable needle cylinder, of a set of separably operable devices, pattern mechanism, selective means controlled by the pattern mechanism and operable thereby to selectively control the operation of said devices, driving means and mechanism operable therefrom to rotate and oscillate the needle cylinder, means operable from the driving means to impart an intermittent movement to said pattern mechanism, and means operable from the driving means to arrest the intermittent movement of the pattern mechanism in a change from rotation to oscillation without stopping the machine.

30 9. In a circular knitting machine, the combination with devices whose operation is to

be selectively controlled, of pattern mechanism and means operable thereby to selectively control the operation of said devices, driving means and mechanism operable therefrom to rotate and oscillate the needle cylinder, a pawl and ratchet adapted to operate said pattern mechanism, means operable from the driving means to operate said pawl, a pawl guard, and means operable from the driving means, in a change from rotation to oscillation, to move said guard and render the pawl, while it continues to operate, inoperative to drive the ratchet and the pattern mechanism.

35 10. In a circular knitting machine, the combination with devices whose operation is to be selectively controlled, of secondary pattern mechanism and means operated thereby to selectively control the operation of said devices, driving means and mechanism operable therefrom to rotate and oscillate the needle cylinder, a pawl and ratchet mechanism adapted to operate the secondary pattern mechanism, means operable from the driving means to operate the pawl, a pawl guard adapted to render the pawl inoperative, primary pattern mechanism operable from the driving means and comprising a cam, and a lever operable from said cam and adapted to move said pawl guard into operative positions, said cam engaging said lever during one of the periods of the oscillation of the needle cylinder.

40 11. In a circular knitting machine, the combination with a rotatable needle cylinder, of selectively operable devices, pattern mechanism, selective means controlled by the pattern mechanism and operable thereby to selectively control the operation of said devices, driving means and mechanism operable therefrom to rotate and oscillate the needle cylinder, means operable from the driving means to impart an intermittent movement to said pattern mechanism, and means to arrest the intermittent movement of the pattern mechanism after the pattern mechanism has reached a predetermined point in its intermittent movement, said arresting means comprising cooperative devices respectively operable from the driving means and carried by the pattern mechanism, said arresting means being rendered inoperative in the subsequent change from oscillation to rotation.

45 12. In a circular knitting machine, the combination with a rotatable needle cylinder, of selectively operable devices, pattern mechanism, selective means controlled by the pattern mechanism and operable thereby to selectively control the operation of said devices, driving means and mechanism operable therefrom to rotate and oscillate the needle cylinder, means operable from the driving means to impart an intermittent movement to said pattern mechanism, means

to arrest the intermittent movement of the pattern mechanism after the pattern mechanism has reached a predetermined point in its intermittent movement, said arresting means comprising cooperative devices respectively operable from the driving means and carried by the pattern mechanism, and another device operable from the driving means to render said arresting means inoperative and positively restart the pattern mechanism.

13. In a circular knitting machine, the combination with a rotatable needle cylinder, of selectively operable devices, pattern mechanism, selective means controlled by the pattern mechanism and operable thereby to selectively control the operation of said devices, driving means and mechanism operable therefrom to rotate and oscillate the needle cylinder, means operable from the driving means to impart a step-by-step movement to said pattern mechanism, and means to arrest the step-by-step movement of the pattern mechanism after the pattern mechanism has reached a predetermined point in its step-by-step movement, said arresting means comprising cooperative devices respectively operable from the driving means and carried by the pattern mechanism, and means to subsequently render said arresting means inoperative.

14. In a circular knitting machine, the combination with a rotatable needle cylinder, of selectively operable devices, pattern mechanism, selective means controlled by the pattern mechanism and operable thereby to selectively control the operation of said devices, driving means and mechanism operable therefrom to rotate and oscillate the needle cylinder, a pawl and ratchet adapted to operate said pattern mechanism, means operable from the driving means to operate said pawl, a pawl guard, and devices operable respectively by the pattern mechanism and the driving means and adapted, after the pattern mechanism has reached a predetermined point in its movement, to cooperate to move said guard into position to render said pawl inoperative to drive the ratchet and the pattern mechanism.

15. In a circular knitting machine, the combination with a rotatable needle cylinder, of selectively operable devices, pattern mechanism, selective means controlled by the pattern mechanism and operable thereby to selectively control the operation of said devices, driving means and mechanism operable therefrom to rotate and oscillate the needle cylinder, a pawl and ratchet adapted to operate said pattern mechanism, means operable from the driving means to operate said pawl, a pawl guard, devices operable respectively by the pattern mechanism and the driving means adapted, after the pattern mechanism has reached a predetermined

point in its movement, to cooperate to move said guard into position to render said pawl inoperative to drive the ratchet and the pattern mechanism, and a subsequently operable second pawl adapted to restart the pattern mechanism, disengage said cooperating devices, and again render the first pawl operative to continue the operation of the pattern chain.

16. In a circular knitting machine, the combination with a rotatable needle cylinder, of selectively operable devices, pattern mechanism, selective means controlled by the pattern mechanism and operable thereby to selectively control the operation of said devices, driving means and mechanism operable therefrom to rotate and oscillate the needle cylinder, a pawl and ratchet adapted to operate the pattern mechanism, means operable from the driving means to operate said pawl, a pawl guard adapted to render the pawl inoperative, a shifter carried by said pattern mechanism, primary pattern mechanism operable from the driving means and comprising a cam, a lever operable from said cam and adapted to be moved thereby into position to be subsequently engaged by said shifter and thereby to be given a further movement to move said pawl guard into operative position.

17. In a needle knitting machine, the combination with a rotatable needle cylinder, of selectively operable devices, pattern mechanism, selective means controlled by the pattern mechanism and operable thereby to selectively control the operation of said devices, driving means and mechanism operable therefrom to rotate and oscillate the needle cylinder, a pawl and ratchet adapted to operate the pattern mechanism, means operable from the driving means to operate said pawl, a pawl guard adapted to render the pawl inoperative, a shifter carried by said pattern mechanism, primary pattern mechanism operable from the driving means and comprising a cam, a lever operable from said cam and adapted to be moved thereby into position to be subsequently engaged by said shifter and thereby to be given a further movement to move said pawl guard into operative position, a second pawl operable from said lever and adapted to restart the pattern mechanism, the primary pattern mechanism comprising also a second cam operable subsequently to impart a still further movement to said lever and thereby effect the actuation of the second pawl and a disengagement of said shifter and lever.

18. In a circular knitting machine, the combination with a rotatable needle cylinder, of selectively operable devices, pattern mechanism, selective means controlled by the pattern mechanism and operable thereby to selectively control the operation of said devices, driving means and mechanism oper-

able therefrom to rotate and oscillate the needle cylinder, means operable from the driving means to impart an intermittent movement to said pattern mechanism, and stop mechanism operable from the driving means to arrest the intermittent movement of the pattern mechanism in one change from rotation to oscillation and to arrest the intermittent movement of the pattern mechanism in timed relation to another change from rotation to oscillation when said pattern mechanism reaches a predetermined point in its intermittent movement.

19. In a circular knitting machine, the combination with a rotatable needle cylinder, of selectively operable devices, pattern mechanism, selective means controlled by the pattern mechanism and operable thereby to selectively control the operation of said devices, driving means and mechanism operable therefrom to rotate and oscillate the needle cylinder, means operable from the driving means to impart an intermittent movement to said pattern mechanism, stop mechanism operable from the driving means to render said pattern mechanism operating means inoperative in one change from rotation to oscillation and to render said pattern mechanism operating means inoperative in timed relation to another change from rotation to oscillation when said pattern mechanism reaches a predetermined point in its subsequent movement, said stop mechanism being rendered inoperative in timed relation to changes from oscillation to rotation.

20. In a circular knitting machine, the combination with selectively operable devices, of selecting means controlling the operation of said devices, a lever adapted to operate the selecting means, pattern mechanism comprising lugs adapted to operate said lever, means to operate the pattern mechanism, means to move said lever to such position that said lugs will not operate it and whereby the selecting means is at the same time rendered inoperative, and means including the pattern chain itself adapted to subsequently render the driving means for the pattern mechanism inoperative.

21. In a circular knitting machine, the combination with devices adapted to independent operation, of secondary pattern mechanism controlling the operation of said devices, mechanism to drive the secondary pattern mechanism, primary pattern mechanism, and means operable by the primary pattern mechanism to render the secondary pattern mechanism, while being driven, inoperative to control the operation of said devices, the secondary pattern mechanism being also adapted to positively so operate said means as to arrest the movement of the secondary pattern mechanism.

22. In a circular knitting machine, in combination, a plurality of chains of levers, a

reciprocatory member carrying the lever of each chain that is adapted to actuate another lever of the same chain, a selector adapted to move the first lever of any chain into actuating position, means to operate the reciprocatory member, and pattern mechanism adapted to position the selector.

23. In a circular knitting machine, the combination with driving means and mechanism operable therefrom, of selecting means movable into different positions to render said mechanism selectively operative, a pattern device operable from the driving means and controlling the operation of the selector, the pattern device being removable and replaceable by another similar pattern device adapted to produce a different operation of the selecting means, means to render the selecting means inoperative to render said mechanism operative without arresting the operation of the pattern device from the driving means, and means subsequently actuatable by the pattern device to arrest its own movement at a definite point.

24. In a circular knitting machine, the combination with mechanism adapted to cooperate in the knitting operation, of a pattern device, driving means and connections adapted to alternately rotate and oscillate the needle cylinder and also to operate said mechanism and said pattern device, selecting means movable into different positions to render said mechanism selectively operative, means controlling the operation of the selector by the pattern device, the pattern device being removable and replaceable by another similar pattern device adapted to produce a different operation of the selecting means, and means to render the pattern device inoperative during oscillation of the needle cylinder and to render it again operative upon resumption of rotation of the needle cylinder.

25. In a circular knitting machine, the combination with driving means and of different mechanisms operable directly thereby, of selecting means independent of said mechanisms but movable into different positions to selectively render any of said mechanisms operable by said driving means, a pattern device controlling the position of the selecting means and operable from said driving means, the pattern device comprising a chain and lugs thereon of different heights and being readily removable, while the selector remains undisturbed, and replaceable by another pattern chain adapted to produce a different operation of the selecting means.

26. In a circular knitting machine, the combination with a rotatable cylinder and other mechanism adapted to cooperate in the knitting operation, driving means and connections therefrom adapted to alternately rotate and oscillate said cylinder and connections therefrom adapted to operate said mechanism, said mechanism including a plu-

rality of elements of a single selector movable into an operable position with relation to any one of said elements, a secondary pattern device controlling the position of the selector, and a primary pattern device controlling the operation of the secondary pattern device, the secondary pattern device being removable and replaceable by another similar secondary pattern device without stopping the machine while said cylinder is being oscillated by the specified connections from the driving means.

27. In a circular knitting machine, the combination with a rotatable cylinder and other mechanism adapted to cooperate in the knitting operation, driving means and connections therefrom adapted to alternately rotate and oscillate said cylinder and connections therefrom adapted to operate said mechanism, of selecting means movable into different positions to render said mechanism selectively operable, a secondary pattern device controlling the position of the selecting means, and a primary pattern device controlling the operation of the secondary pattern device, the secondary pattern device being removable and replaceable by another similar secondary pattern device without stopping the machine while said cylinder is being oscillated by the specified connections from the driving means, and means to arrest the movement of the substituted secondary pattern device and properly position it for operation following the subsequent shift from oscillation to rotation.

28. In a circular knitting machine, the combination with driving means and mechanism operable therefrom, of selecting means movable into different positions to render said mechanism selectively operative, a pattern device operable from the driving means and controlling the operation of the selecting means, the pattern device comprising a turnable member and a pattern element which is removable and replaceable, without stopping the machine, by another similar pattern element adapted to produce a different operation of the selecting means, and means subsequently actuatable by the substituted pattern element to stop the movement of the turnable member and arrest its own movement at a definite point.

29. In a circular knitting machine, the combination with driving means and mechanism operable therefrom, of selecting means movable into different positions to render said mechanism selectively operative, a pattern device operable from the driving means and controlling the operation of the selecting means, the pattern device comprising a turnable member and a pattern element which is removable and replaceable, without stopping the machine, by another similar pattern element adapted to produce a different operation of the selecting means, a primary pat-

tern device, means operable therefrom to control the operation of the turnable member, and means carried by the substituted pattern element adapted to cooperate with the means operable from the primary pattern device to stop the movement of the turnable member and arrest the movement of the substituted element at a definite point.

30. In a circular knitting machine, the combination with devices adapted to cooperate in the knitting operation, secondary pattern mechanism controlling the operation of said devices, means to drive the secondary pattern mechanism, primary pattern mechanism, and means operable by said primary pattern mechanism to render the secondary pattern mechanism inoperative, while it continues being driven, to control the operation of said devices, and by the secondary pattern mechanism to render its own driving means inoperative to drive.

31. In a circular knitting machine, the combination with devices adapted to independent operation, of primary pattern mechanism and secondary pattern mechanism, mechanism to drive the secondary pattern mechanism, means, interposed between the two pattern mechanisms and also between the two pattern mechanisms and said devices, operable by the secondary pattern mechanism to both control the operation of said devices and to render said driving mechanism inoperative to drive the secondary pattern mechanism, and being also operable by the primary pattern mechanism to again render said driving mechanism operative.

32. In a circular knitting machine, the combination with devices adapted to independent operation and whose operation is controlled by pattern mechanism, means to drive said pattern mechanism, said pattern mechanism comprising primary pattern mechanism and secondary pattern mechanism, a lever operable directly by the primary pattern mechanism to render the secondary pattern mechanism, while continuing to be driven, inoperative to operate said devices, said lever being also operable directly by the secondary pattern mechanism to arrest the movement of the secondary pattern mechanism, said lever being also operable by the primary pattern mechanism to render said driving means again operative to drive the secondary pattern mechanism.

33. In a circular knitting machine, the combination with devices adapted to independent operation, of primary pattern mechanism and secondary pattern mechanism, a lever interposed between the two pattern mechanisms and also between the two pattern mechanisms and said devices, means to drive the secondary pattern mechanism, said lever being operable directly by each pattern mechanism to control the operation of said devices and being also operable by the sec-

ondary pattern mechanism to render said driving means inoperable to drive the secondary pattern mechanism and being also operable by the primary pattern mechanism to 5 render said driving means again operative to drive the secondary pattern mechanism.

34. In a circular knitting machine, the combination with a needle cylinder and other mechanism adapted to cooperate with the 10 needles during relative rotation or oscillation of the cylinder and mechanism, of a set of separably operable devices, pattern mechanism, selective means controlled by the pattern mechanism and operable thereby to selectively 15 control the operation of said devices, driving means and mechanism operable therefrom to relatively rotate and oscillate the needle cylinder and cooperating mechanism, means operable from the driving 20 means to impart an intermittent movement to said pattern mechanism, and means operable from the driving means to arrest the intermittent movement of the pattern mechanism in a change from rotation to oscillation 25 without stopping the mechanism.

35. In a circular knitting machine, the combination with a needle cylinder and other mechanism adapted to cooperate with the needles during relative rotation or oscillation 30 of the cylinder and mechanism, of selectively operable devices, pattern mechanism, selective means controlled by the pattern mechanism and operable thereby to selectively 35 control the operation of said devices, driving means and mechanism operable therefrom to relatively rotate and oscillate the needle cylinder and cooperating mechanism, means operable from the driving means to impart an intermittent movement to said 40 pattern mechanism, and means to arrest the intermittent movement of the pattern mechanism after the pattern mechanism has 45 reached a predetermined point in its intermittent movement, said arresting means comprising cooperative devices respectively operable from the driving means and carried by the pattern mechanism, said arresting means being rendered inoperative in the subsequent change from oscillation to rotation.

36. In a circular knitting machine, the combination with a needle cylinder and other mechanism adapted to cooperate with the needles during relative rotation or oscillation of the cylinder and mechanism, of selectively 55 operable devices, pattern mechanism, selective means controlled by the pattern mechanism and operable thereby to selectively control the operation of said devices, driving means and mechanism operable 60 therefrom to relatively rotate and oscillate the needle cylinder and cooperating mechanism, means operable from the driving means to impart an intermittent movement to said pattern mechanism, means to arrest the intermittent movement of the pattern mecha-

nism after the pattern mechanism has reached a predetermined point in its intermittent movement, said arresting means comprising cooperative devices respectively operable from the driving means and carried by the pattern mechanism, and another device operable from the driving means to render said arresting means inoperative and positively restart the pattern mechanism. 70

37. In a circular knitting machine, the combination with a needle cylinder and other mechanism adapted to cooperate with the needles during relative rotation or oscillation of the cylinder and mechanism, of selectively operable devices, pattern mechanism, selective means controlled by the pattern mechanism and operable thereby to selectively 75 control the operation of said devices, driving means and mechanism operable therefrom to relatively rotate and oscillate the needle cylinder and cooperating mechanism, means operable from the driving means to impart a step-by-step movement to said pattern mechanism, and means to arrest the step-by-step movement of the pattern mechanism after the pattern mechanism has reached a predetermined point in its step-by-step movement, said arresting means comprising cooperative devices respectively operable from the driving means and carried by the pattern mechanism, and means to subsequently render said arresting means inoperative. 90

38. In a circular knitting machine, the combination with a needle cylinder and other mechanism adapted to cooperate with the needles during relative rotation or oscillation of the cylinder and mechanism, of selectively operable devices, pattern mechanism, selective means controlled by the pattern mechanism and operable thereby to selectively 100 control the operation of said devices, driving means and mechanism operable therefrom to relatively rotate and oscillate the needle cylinder and cooperating mechanism, a pawl 105 and ratchet adapted to operate said pattern mechanism, means operable from the driving means to operate said pawl, a pawl guard, and devices operable respectively by the pattern mechanism and the driving means and adapted, after the pattern mechanism has reached a predetermined point in its movement, to cooperate to move said guard into position to render said pawl inoperative to 110 drive the ratchet and the pattern mechanism. 115

39. In a circular knitting machine, the combination with a needle cylinder and other mechanism adapted to cooperate with the needles during relative rotation or oscillation of the cylinder and mechanism, of selectively operable devices, pattern mechanism, selective means controlled by the pattern mechanism and operable thereby to selectively 120 control the operation of said devices, driving means and mechanism operable 125

therefrom to relatively rotate and oscillate the needle cylinder and cooperating mechanism, a pawl and ratchet adapted to operate said pattern mechanism, means operable 5 from the driving means to operate said pawl, a pawl guard, devices operable respectively by the pattern mechanism and the driving means adapted, after the pattern mechanism has reached a predetermined point in its 10 movement, to cooperate to move said guard into position to render said pawl inoperative to drive the ratchet and the pattern mechanism, and a subsequently operable second pawl adapted to restart the pattern mechanism, disengage said cooperating devices, and again render the first pawl operative to continue the operation of the pattern chain.

40. In a circular knitting machine, the combination with a needle cylinder and other 20 mechanism adapted to cooperate with the needles during relative rotation or oscillation of the cylinder and mechanism, of selectively operable devices, pattern mechanism, selective means controlled by the pattern 25 mechanism and operable thereby to selectively control the operation of said devices, driving means and mechanism operable therefrom to relatively rotate and oscillate the needle cylinder and cooperating mechanism, a pawl and ratchet adapted to operate the 30 pattern mechanism, means operable from the driving means to operate said pawl, a pawl guard adapted to render the pawl inoperative, a shifter carried by said pattern mechanism, primary pattern mechanism operable 35 from the driving means and comprising a cam, a lever operable from said cam and adapted to be moved thereby into position to be subsequently engaged by said shifter 40 and thereby to be given a further movement to move said pawl guard into operative position.

41. In a circular knitting machine, the combination with a needle cylinder and other 45 mechanism adapted to cooperate with the needles during relative rotation or oscillation of the cylinder and mechanism, of selectively operable devices, pattern mechanism, selective means controlled by the pattern 50 mechanism and operable thereby to selectively control the operation of said devices, driving means and mechanism operable therefrom to relatively rotate and oscillate the needle cylinder and cooperating mechanism, a pawl 55 and ratchet adapted to operate the pattern mechanism, means operable from the driving means to operate said pawl, a pawl guard adapted to render the pawl inoperative, a shifter carried by said pattern mechanism, 60 primary pattern mechanism operable from the driving means and comprising a cam, a lever operable from said cam and adapted to be moved thereby into position to be subsequently engaged by said shifter and there- 65 by to be given a further movement to move

said pawl guard into operative position, a second pawl operable from said lever and adapted to restart the pattern mechanism, the primary pattern mechanism comprising also a second cam operable subsequently to 70 impart a still further movement to said lever and thereby effect the actuation of the second pawl and a disengagement of said shifter and lever.

42. In a circular knitting machine, the 75 combination with a needle cylinder and other mechanism adapted to cooperate with the needles during relative rotation or oscillation of the cylinder and mechanism, of selectively operable devices, pattern mechanism, selective means controlled by the pattern mechanism and operable thereby to selectively control the operation of said devices, driving means and mechanism operable therefrom to relatively rotate and oscillate the 80 needle cylinder and cooperating mechanism, means operable from the driving means to impart an intermittent movement to said pattern mechanism, and stop mechanism operable from the driving means to arrest the 85 intermittent movement of the pattern mechanism in one change from rotation to oscillation and to arrest the intermittent movement of the pattern mechanism in timed relation to another change from rotation to oscillation when said pattern mechanism reaches a 90 predetermined point in its intermittent movement.

43. In a circular knitting machine, the combination with a needle cylinder and other 100 mechanism adapted to cooperate with the needles during relative rotation or oscillation of the cylinder and mechanism, of selectively operable devices, pattern mechanism, selective means controlled by the pattern mechanism and operable thereby to selectively control the operation of said devices, driving means and mechanism operable 105 therefrom to relatively rotate and oscillate the needle cylinder and cooperating mechanism, means operable from the driving means to impart an intermittent movement to said pattern mechanism, stop mechanism operable from the driving means to render said 110 pattern mechanism operating means inoperative in one change from rotation to oscillation and to render said pattern mechanism operating means inoperative in timed relation to another change from rotation to oscillation when said pattern mechanism reaches a 115 predetermined point in its subsequent movement, said stop mechanism being rendered inoperative in timed relation to changes from oscillation to rotation.

44. In a circular knitting machine, the 125 combination with a needle cylinder and other mechanism adapted to cooperate with the needles in the knitting operation, driving means and connections therefrom adapted to alternately rotate and oscillate relatively to 130

each other said cylinder and its said cooperating mechanism and connections between the cylinder and mechanism, said mechanism including a plurality of elements, of a single selector movable into an operable position with relation to any one of said elements, a secondary pattern device controlling the position of the selector, and a primary pattern device controlling the operation of the secondary pattern device, the secondary pattern device being removable and replaceable by another similar secondary pattern device without stopping the machine while said cylinder and mechanism are relatively oscillated by the specified connections from the driving means.

45. In a circular knitting machine, the combination with a needle cylinder and other mechanism adapted to cooperate with the needles in the knitting operation, driving means and connections therefrom adapted to alternately rotate and oscillate relatively to each other said cylinder and its said cooperating mechanism and connections between the cylinder and mechanism, of a selector movable into different positions to render said mechanism selectively operable, a secondary pattern device controlling the position of the selector, and a primary pattern device controlling the operation of the secondary pattern device, the secondary pattern device being removable and replaceable by another similar secondary pattern device without stopping the machine while said cylinder and mechanism are relatively oscillated by the specified connections from the driving means and means to arrest the movement of the substituted secondary pattern device and properly position it for operation following the subsequent shift from oscillation to rotation.

In testimony of which invention, I have hereunto set my hand, at Philadelphia, Pennsylvania, on this 13th day of June, 1928.

HAROLD E. HOUSEMAN.
